(57) **CLAIM**

The ornamental design for a split-top bedding, as shown and described.

DESCRIPTION

FIG. 1 shows a perspective view of the split-top bedding showing my new design;

FIG. 2 shows a top view thereof;

FIG. 3 shows a front view thereof;

FIG. 4 is the right side view thereof;

FIG. 5 is the bottom view thereof;

FIG. 6 is the left side view thereof;

FIG. 7 is the back view thereof; and,

FIG. 8 is a front view in an alternative position.

The cross-hatched shading is fragmentally shown for convenience of illustration, it being understood that the cross-hatched shading is uniformly continued over the surfaces on which it appears.

The broken lines in the figures show stitching and form no part of the claimed design. Additional dashed lines in FIG. 1 represent environment and form no part of the claimed design.
